Primary Examiner — Jae Liang*Assistant Examiner* — Caleb M Baker(74) *Attorney, Agent, or Firm* — Fitch, Even, Tabin & Flannery LLP(57) **CLAIM**

The ornamental design for an electronic component portion as shown and described.

DESCRIPTION

FIG. 1 is a bottom perspective view of an electronic component portion in accordance with our new design that disclaims the number of turns in the electronic component portion via dash-dot boundary lines;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines in the figures illustrate portions of the electronic component portion that form no part of the claimed design. The dash-dot lines depict the boundaries of the claimed design that form no part of the claimed design.
